UNITED STATES PATENT OFFICE.

WILLIAM CLIMIE, OF MOSSSEND, LANARKSHIRE, SCOTLAND.

GAS PRODUCER.

Application filed June 15, 1922, Serial No. 568,523, and in Great Britain June 15, 1921.

My invention relates to gas producers, having particular relation to fuel rakes.

An important object of my invention is to provide a rake which is particularly applicable to gas generators operating at high temperatures.

Another object of my invention is to provide a simple and easily constructed water cooled rake having curved surfaces, whereby the same may slide over the fresh fuel.

A further object of my invention is to provide apparatus of the class described which is provided with relatively short teeth and relatively long cutting knives, together with means automatically operable to maintain the rake on the upper surface of the fuel.

In carrying my invention into effect, I provide a vertical and rotatable trunk which is positioned centrally at the upper part of a gas producer, the rotatable trunk being provided with a horizontal division wall. Two rods or tubes, which are adapted to slide vertically through said wall into the producer, are fitted at their lower ends to a horizontal structure forming the rake. The horizontal structure may comprise a horizontal member having flat portions and upwardly curved portions so arranged that as the cylinder or trunk, and, therefore, the vertical rods, rotate about the vertical center line of the producer the under surfaces of the flat portions ride upon the surface of the fuel. Hence, it can be seen as fresh fuel is inserted into the producer from the top, the curved portions cause the rake structure to mount over the same so that its position on the top of the fuel is maintained.

The under surfaces of the flat portions are provided with raking teeth and cutting or tearing knives for the purpose of raking or scattering the fuel and cutting through the same to prevent caking. The teeth and knives are arranged in such manner that the whole surface of the fuel is acted upon, and are preferably disposed at tangents to circles, the radii of which are the distances of the teeth and knives from the vertical center line of the producer.

With these and other objects and applications in mind, my invention further consists in the combination, and arrangement and constructional details hereinafter described and claimed and illustrated in the accompanying drawings, in which

Figure 1 is a sectional elevation of the upper end of a gas producer provided with a fuel rake constructed in accordance with my invention; and

Figs. 2, 3 and 4 are enlarged top plan, side elevational and end views, respectively, of the fuel rake structure of Fig. 1.

In the embodiment of my invention shown in the drawings, only such details of the general structure are illustrated as are necessary to a clear understanding of my present invention. The gas producer or generator therein shown may comprise two cylindrical casings 1 and 2 positioned vertically and concentrically, one within the other, so that a water space 3 is formed therebetween. The space 3 is closed at its lower end (not shown), while the corresponding end of the inner cylindrical casing 1 is open. An air blast cone (not illustrated) is positioned centrally at the lower end of said inner casing.

The inner one of the two concentric casings is preferably shorter than the outer one so that the water space 3 between the two casings opens into a steam space 4 formed between the tops of the two casings 1 and 2. The upper ends of the two casings are closed by plates 5 and 6, respectively.

The cover plate 5 of the inner casing 1 is provided with a vertical cylinder 7 which passes through the cover plate 6 of the outer casing 2 and it is provided near its upper end with a hopper entrance 8 and a gas outlet 9. A trunk 11 is located centrally within the vertical cylinder 7 and it is closed midway the ends thereof by a horizontal plate or division wall 12.

The upper end of the cylinder 7 is closed by a rotatable plate 13 mounted upon ball or roller bearings 14 and it is further provided with a water seal 15. The inner trunk 11 is secured to the plate 13, so that it is rotated as the plate 13 is moved, for example by a worm and wheel 16.

A pair of vertical rods or tubes 17 pass downwardly through the inner trunk 11 and the horizontal division wall 12 of same into the upper end of the gas producer. The lower ends of the rods or elements 17, which are positioned within the producer, are fitted to a cross rod or tube 18 which carries and forms parts of the fuel rake. Sleeves forming water-seals 19 are fitted to the upper side of the well 12 of the inner trunk 110

11 and surround the vertical tubular elements 17. Suitably positioned guide rollers or the like 20 constituting antifriction means for the rods or tubes 17 may be mounted on 5 the inner trunk 11 just beneath the horizontal closure plate 12.

The fuel rake proper is formed of two parts 21 and 22, each part being similarly constructed, but secured to opposite ends of 10 the cross tube or rod 18 and extending only half way the length of the same. The parts 21 and 22 of the rake are located respectively behind each half of said tube 18 and comprise curved box-like structures 23 and 24, 15 having operative connections 25 and 26 with the tube 18, respectively. Each box-like structure comprises an upwardly curved portion 32 and a horizontal portion 39, as shown in the drawings. Adjacent ends of the boxes 20 23 and 24 are operatively associated by means of a pipe 27, whereby a cooling fluid may flow from one box 23 to the other. The outer edges of the boxes 23 and 24, which are parallel to the cross rod 18, may be stiffened 25 by means of plates 28 having downwardly projecting teeth 29 and comparatively long cutting or tearing knives 31.

In operation, as the inner trunk 11 is rotated, it carries with it the two vertical rods 30 or tubes 17 which in turn rotate the cross rod or tube 18 about the vertical center line of the gas producer, that is, the cross rod 18 travels over the surface of the fuel within the gas producer. The rakes proper are arranged 35 behind the cross rod 18 as it travels so that they are dragged over the surface of the fuel. The teeth 29 of the rake scatter and evenly distribute or rake the fuel while the long knives 31 cut into the fuel so as to 40 keep the same broken up. Curved portions 32 of the boxes 23 and 24 forming the rake prevent the same from being buried as fresh fuel is inserted into the generator through the inlet opening 8. These curved portions 45 32 cause the rake to mount over the fuel and to maintain its position on the top of the same.

The teeth 29 and knives 31 of the rake structure are so positioned that the full surface 50 of the fuel (not shown) may be operated upon and preferably the points of the teeth and the cutting edges of the knives are disposed at tangents to circles, the radii of which are the distance of said teeth and knives from the vertical center line of the producer.

The weight of the rake and its vertical rods or tubes 17 may be balanced by a weight 33 which is mounted within the inner trunk 60 11 and which is fitted to ropes or the like 34 passing over guide pulleys or the like 35. The weight 33 may comprise a water tank, whereby the pressure with which the rake rests upon the fuel may be varied.

65 When the gas producer is operating at

very high temperatures, the rake structure may be cooled by circulating a cooling fluid medium through the vertical and horizontal tubes 17 and 18 and the interconnected box-like structure 23 and 24, the direction of flow 70 being, say down one of the tubes 17, out along one half of the cross tube 18 to the outer end of the box 23, through the connected boxes 23 and 24 and returning along the other half of the tube 18 to the other tube 17. The upper ends of the tubes 17 may be connected to the space 3, but this has not been shown.

A coil of piping 37 may be rigidly positioned in the upper end of the gas producer so as to encircle the rotary trunk 11. One end of the piping 37 is connected to a supply pipe (not shown) while the other end is operatively associated with the space 3, whereby a cooling medium may be circulated through the piping 37 and the space 3.

80 One or more vertical brushes 38, say of circular or spiral form, may be positioned between the upright cylinder 7 and the inner trunk 11 and preferably secured to the outside surface of the latter, whereby the inside surface of the cylinder 7 may be kept 90 clean and free from carbon.

95 While I have shown only one embodiment of my invention, for the purpose of describing the same and illustrating its principles of construction and of operation, it is apparent that various changes and modifications may be made therein without departing from the spirit of my invention and I desire, therefore, that only such limitations shall be imposed thereon as are indicated in the appended claims or as are demanded by the prior art.

I claim:

1. In a gas producer, in combination, a 100 casing; a rotatable trunk positioned therein; a division wall provided in said trunk; a plurality of rods adapted to slide through said division wall; and a rake structure secured to said rods and comprising a member having curved and flat portions, certain of said portions being provided with fuel raking teeth and fuel cutting knives.

115 2. In a gas producer, in combination, a casing; a vertical cylinder surrounding a rotatable trunk positioned at the upper part of said casing; a horizontal division wall provided in said trunk; a plurality of rods adapted to slide vertically through said division wall; a horizontal member secured to the lower ends of said rods; members secured to said horizontal member and extending outwardly therefrom on each side of the same; teeth and knives secured to 120 said outwardly extending members, whereby the fuel may be raked or cut; and a counterbalance automatically operable to maintain said last-mentioned members on the upper surface of the fuel.

3. In a gas producer, in combination, a casing; a rotatable trunk arranged therein; a division wall provided in said trunk; a plurality of rods adapted to slide through 5 said division wall; a member secured to one end of said rods; members secured to said first-mentioned member and extending outwardly therefrom on each side of the same; and raking teeth and cutting knives secured 10 to said outwardly extending members and having their points and cutting edges disposed at tangents to circles, the radii of which are the distances of said teeth and knives from the vertical center line of the 15 producer.
4. In a gas producer, in combination, a rotatable trunk; a division wall provided in said trunk; a plurality of rods adapted to move through said division wall; a tubular 20 element secured to said plurality of rods; and box-like structures constituting a rake agitator for the fuel secured to said tubular element and located one behind each half of, and on opposite sides of the same turbulent 25 element, said box-like structures having curved surfaces.
5. In a gas producer, in combination, a casing; a vertical cylinder surrounding a rotatable trunk positioned at the upper part 30 of said casing; a division wall provided in said trunk; rods adapted to move through said division wall; a rake structure carried at one end of said rods, said rake structure comprising portions provided with fuel raking teeth and fuel cutting knives; and brushes effective upon a movement of said trunk to cause the sweeping of the inner surface of said cylinder. 35
6. In a gas producer, in combination, a casing; a rotatable trunk positioned in the upper end of said casing; a horizontal division wall in said trunk, said wall being provided with a plurality of openings; a rod extending through each of said openings; a plurality of teeth operative on the fuel in the producer; and means mounted on the ends of said rods for supporting said teeth. 45
7. In a gas producer, the combination with a casing; of a rotatable trunk positioned in the upper end of said producer; a horizontal division wall in said trunk, said wall being provided with a plurality of openings; a rod extending through each of said openings; means forming seals for said 50
- rods; a rake structure for the fuel mounted 55 on said rods; and a plurality of fuel raking teeth and fuel cutting knives secured to said rake structure.
8. In a gas producer, in combination, a rotatable trunk; a division wall in said 60 trunk, said division wall being apertured; an element extending through said apertured wall; a rake structure for the fuel in the producer secured to said element; means secured to said element operable to cause 65 said element to mount over fresh fuel as same is charged into the producer; and antifriction means for said movable element.
9. In a gas producer, in combination, a 70 casing; a trunk positioned in the upper end of said producer; a division wall in said trunk, said division wall being apertured for the reception of vertically extending elements; a rake structure for the fuel secured 75 to one end of said elements; means secured to the other end of said elements operable to cause said elements to mount over fresh fuel as same is charged into the producer; and antifriction means for said movable elements 80 secured on said cylinder on one side of said division wall.
10. In a gas producer, the combination with a casing; of a rotatable trunk positioned in the upper end of said casing; a 85 horizontal division wall in said trunk; a plurality of vertically movable tubular elements extending through said trunk; a rake for the fuel comprising a hollow box-like structure carried by said tubular elements, said elements and said rake having a circulating 90 cooling system; and a plurality of teeth secured to said rake structure.
11. In a gas producer, the combination with a rotatable trunk; a horizontal division 95 wall in said trunk; a plurality of movable tubular elements positioned in said trunk; a rake structure for the fuel in the producer comprising a hollow box-like structure carried by said tubular elements, said elements 100 and said rake structure having a circulating cooling system; antifriction means for guiding said movable tubular elements; and means positioned in said rotatable trunk for automatically maintaining said rake 105 structure on the upper surface of the fuel.

WILLIAM CLIMIE.
